(57) **CLAIM**

The ornamental design for a hinge, as shown and described.

DESCRIPTION

FIG. 1 is a front, right, top perspective view of a hinge, showing my new design;

FIG. 2 is a rear, left, bottom perspective view thereof;

FIG. 3 is a front elevational view of the reduced scale thereof;

FIG. 4 is a rear elevational view of the reduced scale thereof,

FIG. 5 is a left side view of the reduced scale thereof;

FIG. 6 is a right side view of the reduced scale thereof;

FIG. 7 is a top plan view of the enlarged scale thereof;

FIG. 8 is a bottom plan view of the enlarged scale thereof;

FIG. 9 is a front, right, top perspective view thereof,

indicating the usage environment;

FIG. 10 is a front, left, top perspective view of its reduced scale, indicating the usage environment;

FIG. 11 is an enlarged view of detail 11 in FIG. 10;

FIG. 12 is an enlarged view of detail 12 in FIG. 10;

FIG. 13 is an enlarged view of detail 13 in FIG. 10;

FIG. 14 is an enlarged view of detail 14 in FIG. 10; and,

FIG. 15 is an enlarged view of detail 15 in FIG. 10.

The broken lines depict portions of the hinge and an environment of use and form no part of the claim.
